UNITED STATES PATENT OFFICE

2,448,343

PROJECTILE

Solis Myron Zandmer, Los Angeles, Calif.

Application December 14, 1942, Serial No. 468,971

8 Claims. (Cl. 102—92.5)

1

The invention relates to improvements in a projectile and barrel or bore of a gun or cannon or other firearm.

An object of the invention is the provision of means to reduce the friction and loss of energy in the passage of the projectile through the bore of the cannon while utilizing spiral tracks, grooves, or guides in the bore to impart a rotary motion or spin to the projectile.

Another object is to provide a positively interconnected friction reducing spirally disposed guiding means between the projectile and the barrel or cannon bore, positively constraining it to a rotary motion in its passage through the cannon.

Another object is to provide for a substantial reduction of recoil by reason of the provision of the friction-reducing means according to the invention, thereby permitting of lighter, simpler, and more mobile construction of guns or cannon and of recoil mechanism, especially desirable for tank or aircraft cannon, which can consequently be of larger size.

A further object is the provision of means providing for friction reducing bearings at more than one point along the projectile and also to provide means enabling change in the rate of the spiral of the rifling in the barrel of the cannon to change the rate of spin or rotary motion of the projectile.

Other objects will appear hereinafter.

In the drawings which are diagrammatic

Figure 1 is a small scale view of a projectile according to the invention in which balls are mounted.

Fig. 2 is an enlarged fragmentary section on line 2—2 of the projectile of Fig. 1, in place in the barrel of the firearm also shown in section.

Fig. 3 is an enlarged view of a ball between the projectile and bore.

Fig. 4 is a view of a projectile embodying a preferred modification of the invention, and Fig. 5 is an enlarged section on line 5—5 of Fig. 4, also showing the barrel of the firearm in section.

Fig. 6 is a view of a projectile embodying a further modification, and Fig. 7 is a section on line 7—7 of Fig. 6, and also showing the barrel of the firearm in section.

Fig. 8 is a sectional view showing a detail.

Fig. 9 is an enlarged sectional view of a modification of the ball mounting in the projectile, and Fig. 10 is another view of the same showing the ball received in and engaging the spiral groove or track in the bore of the cannon or firearm.

Fig. 11 is a view similar to Fig. 9 showing the

ball received in the spiral groove diagrammatically shown.

Fig. 12 is a top plan view of the ball mounting of Fig. 9.

5 Fig. 13 is an enlarged sectional view of a further modification of the ball mounting in the projectile, and Fig. 14 is another view of the same showing the ball received in the spiral groove or track in the bore of the cannon or firearm.

10 Fig. 15 is a view similar to Fig. 13 showing the ball received in the spiral groove diagrammatically shown.

Fig. 16 is a top plan view of the ball mounting of Fig. 13.

15 Fig. 17 is a diagrammatic illustration of a portion of a firearm bore according to the invention, provided with spirally disposed tracks, grooves, or guides for receiving the balls of the projectile and for imparting a rotary motion thereto.

20 Fig. 18 is a diagrammatic illustration of another portion of firearm bore showing spiral tracks or grooves according to the invention, disposed in an increased rate of spiral.

Fig. 19 is a reduced view similar to Fig. 8 of a 25 desirable modification.

In the drawings 1 represents a projectile in which, according to the invention, spaced apart balls 2 are mounted in seats or sockets at fixed positions or locations in the body of the projectile, 30 and are mounted to permit them to rotate in said seats or sockets 3 in the projectile.

The balls may be mounted in the body of the projectile in the seats or sockets 3 provided in any suitable way and by any suitable means, and in 35 the embodiment shown cages or insert members or plugs 4, having the sockets 3 formed thereon, are employed inserted in recesses 5 formed in the body of the projectile.

The cages providing sockets or seats 3 in the projectile are designed to receive a portion of the 40 entire surface of the balls 2, while leaving a portion of the balls exposed and protruding from and beyond the surface of the projectile. The portion of the surface of the ball received in the seat or socket, and the remaining portion protruding from the body of the projectile may be substantially half or more or any portion less than half of the surface of the ball, as may be desired. In the preferred embodiments exemplified in the 45 drawings the balls are disposed so that at least one hundred and twenty degree (120°) arcuate sections thereof engage in the rifling groove and in the projectile body, respectively. In the form of Figs. 1—3 approximately half the ball engages in each. The same is true in the form of Figs.

4-5, and with respect to the balls 2 in the form of Figs. 6-8 (in which the balls 2a are primarily guiding or centering balls, rather than projectile rotating balls). In the form of Figs. 9-12, an arcuate third of the ball is engaged in the projectile body and nearly two arcuate thirds of it in the rifling. In the form of Figs. 13-16 an arcuate third of the ball engages in the rifling and nearly two arcuate thirds in the projectile body. By this arrangement effective shear sections and load distribution are attained.

In this connection it is desirable to so mount each ball in its seat or socket, that there is a minimum of bearing contact between the ball and its seat or socket, so that there will be a minimum of contact points of sliding friction between the ball and its socket as the ball rotates therein.

Spiral grooves or guides 6 are provided in the barrel or bore 7 of the gun or cannon and are of a suitable shape in cross-section, i. e., arcuate or spherical, to receive and to positively guide and constrain the balls seated in the projectile, to the spiral path of the grooves to positively rotate the projectile by means of the ball bearings moving in engagement with the spiral grooves, upon its being projected through the bore. The smooth portions 1a of the projectile between the spaced apart ball bearings are disposed adjacent and to pass over the corresponding smooth portions 7a of the barrel between the spaced spiral grooves and are desirably spaced therefrom by a minimum of clearance sufficient to provide for expansion and contraction under temperature change while desirably maintaining the minimum of clearance at all times. The full load of the projectile in the bore of the gun is then carried by the balls. However, the invention is not limited to this, as relative dimensions may be such that the load of the projectile may be partially or wholly carried by the smooth surfaces 1a of the projectile slidably engaging the smooth surface portions 7a of the barrel, the balls then bearing principally against the sides of the spiral grooves to guide and impart rotation to the projectile.

Desirably the balls 2 may be mounted in spaced apart relation in a circular row around the projectile, as seen in Fig. 1, the balls being disposed for rotation in the seats or sockets 3 which are spaced apart in said circular row so that the protruding part of each of the balls will be in a position such that it will enter one of the spiral grooves 6 of the bore 7 of the cannon or gun. The balls, however, need not form a circular row, but may be disposed on or along the body of the projectile in any desired spaced arrangement so that they are in a position to be received in the spiral grooves in the bore of the gun, which grooves also need not be arranged in any fixed number or relation as to spacing so long as the grooves and balls are made and disposed to cooperate.

If the rate of spiraling of the grooves 6 in the bore is uniform throughout the length of the bore, the balls need not be in a circular row. Also, a second circular row of balls 2 may be provided as seen in Fig. 4 to provide additional bearings and positive guiding means.

If, however, the rate of spiral is changed during the passage through the bore, only a single circular row or group of rotary balls in fixed spaced location in the projectile surface may be used as in Fig. 1, which will be capable of conforming to any change in the rate of spiraling of the grooves.

I also provide by my invention for additional bearings on a projectile for use in a bore having variations in the rate of spiraling of its grooves. These additional bearings, additional to the single circular row of balls in fixed spaced location, are provided by means of one or more rotary rings 8 carrying rotary balls, as indicated at 2a in Figs. 6, 7 and 8, the balls 2a having rolling contact on a surface 9 of the projectile. The rotary ring 8 is designed in any suitable manner to carry the balls 2a for rotation in fixed spaced locations in said ring corresponding to the spacing of the balls 2, Fig. 6. The ring may, for example, be formed in two parts as seen in Fig. 8, comprising an inner ring portion and an outer ring portion and so shaped or formed at the ball recesses, as to conform to the spherical surface of and to retain the balls in the ring for rotation therein. The two parts of the divided ring 8 may be secured together by any suitable means, as rivets or other fastening means 10. The projectile surface or raceway 9 for the balls 2a of the rotary ring 8 may be provided in any suitable manner, and in the embodiment shown may desirably be disposed inwardly of the main surface 1 of the projectile thereby forming a shoulder at 11 against which the rotary ring may have sliding contact. The connection of the nose 1x of the projectile to the body thereof, may be by a screw threaded connection as indicated at 12 in Fig. 8. Desirably the rotary ring 8 may be initially fixed in position on the projectile by any temporary fastening and in the embodiment shown a small frangible spot weld 13 or other fastening is formed between the rotary ring 8 and the shoulder 11, which will be broken upon any change in the rate of spiral of the grooves of the barrel in the passage of the projectile therethrough, to permit the rotary ring to change its rotary position in respect to the projectile to conform to the changed rate of spiral of the grooves, the projectile still being positively guided in the spiral grooves by the single circular row of balls 2 (Fig. 6) in fixed location around the projectile whatever the rate of spiral of the grooves may be. After the temporary seal or fastening 13 is broken, the balls 2a in the rotary ring 8 simply provide bearing for the projectile in its passage in the grooves of the bore and do not serve to impart any rotary motion to the projectile, said rotary motion being imparted to the projectile by the fixed rotary balls 2 in the spiral grooves of the bore. Upon discharge of the projectile from the barrel, there is no further function for the ring 8 and balls 2a and whether or not the ring 8 becomes separated from the projectile is immaterial. However, the nose 1x may desirably be extended in diameter as shown at 1xx in Fig. 19 to hold the rotary ring 8 on the projectile.

Regarding the mounting of the balls 2 in substantially fixed locations in the projectile surface, as seen in Fig. 3, the balls 2 may each be disposed in a socket or seat 3 desirably of somewhat larger diameter than the segment of the spherical surface of the ball, at the plane of contact between the ball and seat, which is substantially the ball diameter in the embodiment shown in Fig. 3 (in which the ball is disposed substantially half in the socket and half protruding from the surface of the projectile and engaged in the spiral groove of the gun bore). Thus in Fig. 3, the seat 3 is desirably made of larger diameter than that of the ball. The ball preferably is temporarily fastened to the bottom of the seat or socket 3 by

any suitable means, as by a frangible screw pin 14, which will hold the ball in its seat in the projectile before the projectile is inserted in the barrel of the piece.

Upon insertion of the projectile in the gun bore with the balls entering the grooves in the bore the temporary fastening or pin 14 will break in the spiral groove as the projectile is moved into the bore and the ball will then engage the larger diameter seat 3 at one point, and also at another point where the ball engages the bottom of the seat.

This is shown also in Figs. 9, 10 and 11, in which the ball mounting is similar to that of Fig. 3 except that in Figs. 9, 10, and 11 more than half of the ball protrudes from the surface of the projectile and is received in the correspondingly shaped groove 6a in the bore of the cannon or firearm, and the seat or socket 3a is accordingly so shaped and constructed as to receive less than half of the ball.

As seen in Fig. 9, the ball is temporarily fastened to the bottom of the socket or seat 3a as by means of soft or frangible pin 14a, and the seat or socket is desirably of somewhat larger diameter than the segment of the spherical surface of the ball, at the plane of contact between the ball and seat. In Fig. 11 the projectile 1 is shown inserted in the bore 1 of the firearm with the ball 2 disposed in the spiral groove 6a, the fastening pin 14a having been broken by the said insertion of the ball into the spiral groove, and the ball then rolled over against the larger diameter seat 3a contacting said seat at the point B and remaining in contact with the substantially flat bottom of the seat in a point contact A, these points providing sliding contact points for the ball turning in its seat as it moves along the guide groove or track 6a in the passage of the projectile through the gun. The seat construction providing contact points B and A represents one means of providing a minimum of sliding friction contact between the ball and its seat, but the invention is not limited thereto, it being obvious that the seat or cage for the rotary ball may be formed in other ways within the invention to minimize the sliding friction contact of the ball in its seat. Fig. 12 shows a top plan view of the ball and projectile in the same position as in Fig. 11.

The balls of Fig. 3 and Fig. 9 after breakage of the fastening pin, cannot become dislodged from the cage while the projectile is passing through the bore, but are free to fall out of the projectile upon discharge of the projectile from the bore of the firearm or cannon.

The ball mounting shown in Figs. 9 to 12 also differs from that of Figs. 1, 2, and 3 in that it embodies a modification applicable to any of the ball mountings, comprising making the recess 5a in the projectile somewhat larger in a circumferential or annular direction around the projectile, than the insert member or ball cage 4a so that space is left at either end of the insert member receiving leaf springs or the like 15. This permits of some lateral "give" or movement of the ball and cage or insert 4a in the enlarged recess 5a in a direction annularly of the projectile as the projectile moves with its balls guided in the spiral grooves. The springs 15 are shown in plan in Fig. 12 and in section in Fig. 10, both of which views also show the enlarged recess 5a and the cage 4a disposed in said recess for some relative sliding movement therein resisted by said springs, under action of the ball in

the cage riding in the spiral groove. This yieldable mounting is a desirable modification of the invention, but the invention is not limited thereto, and the invention is not limited to the rectangular shape of the recesses and cages therein, as they may be of any suitable shape to provide a seat or socket for the balls, and may be round or any other shape instead of the rectangular shape as in Fig. 3.

10 In Figs. 13 to 16 is shown a ball mounting according to the invention in which less than half of the ball 2 protrudes from the surface of the projectile, and rides in a corresponding groove 6b in the bore. The ball may rest on the bottom of the recess 5b or may desirably, as shown, rest upon a flat topper plug or the like 16, screwed or otherwise inserted in the body of the projectile at the bottom of the recess 5b. The ball may be retained in the recess by means of the seat or cage member 4b being of such diameter at its outer end 3b that, while larger than the diameter of the segment of the spherical surface of the ball at the plane of the outer end of the socket member, is smaller than the full diameter of the ball and therefore prevents the ball from dropping out of the seat in the projectile.

15 In Fig. 15 the ball moving in the groove 6b has been rolled against the larger diameter (at this plane) seat 3b and contacts said seat at the point B' for sliding contact therewith in rotation of the ball in its seat. The ball also has a sliding point contact A' with the flat top of the plug 16, as the ball moves along in the groove 6b of the gun barrel.

20

25 Springs 15 in the enlarged recess 5b receiving the cage or insert member 4b for yieldable movement therein may desirably be provided in the embodiment of Figs. 13 to 16 as in that of Figs. 9 to 12, and are also indicated in Figs. 4, 5 and 6 as desirable.

Suitable wadding 17 is provided as indicated in Figs. 1, 4 and 6 to follow the projectile through the bore and of a diameter larger than the projectile to provide a seal or gas check in the bore. The material of the wadding may be any suitable for the purpose capable of withstanding high temperature. Asbestos or mica may be mentioned as materials of a type suitable for the wadding.

Desirably, the space under each ball in its cage, as mounted, may be packed with grease or graphite or other lubricant.

I claim:

1. A projectile having balls rotatably seated in its surface and projecting therefrom and disposed in spaced apart relation, to be received in spaced spiral grooves in a gun bore, the seats for said balls in said projectile having a substantially flat or level inner surface providing substantially a point contact with said ball, and the portion of said seat embracing the ball being designed to provide at least one other point contact with said ball, and means temporarily fastening or pinning said ball to said seat substantially at said contact point on said inner surface, said temporary pin being designed to be broken to free the ball for rotation in its seat, upon entry of the balls in the spaced spiral grooves of the gun bore.

2. A projectile having balls seated for rotation in its surface in spaced relation and projecting therefrom a distance sufficient to extend into spaced spiral grooves in the bore of a gun, said projectile having smooth surface portion between the balls for passage over smooth portions of the gun bore, said projectile having recesses in

the surface thereof, cages in said recesses for receiving said balls, said recesses being larger in area than said cages, so that the cages are laterally shiftable therein, and resilient means disposed in said recesses engaging the cage members and the walls of the recesses and retaining said cages therein in such manner that said cages may shift in said recesses to provide shift of alignment of said balls to adapt them to the spaced spiral grooves of the gun bore.

3. A projectile having a plurality of recesses in the surface thereof at spaced intervals around the projectile, a cage member in each of said recesses, each recess being of a greater dimension than the associated cage measured circumferentially of the projectile, a ball arranged in each cage member and projecting from the surface of the projectile a distance sufficient to extend into spaced spiral grooves in the bore of a gun, and spring means disposed in said recesses and engaging the cage members.

4. In a projectile, spaced projectile-rotating means comprising balls seated for rotation in the surface of the projectile and extending outwardly from the surface of the projectile sufficiently for engaging spaced spiral grooves in the bore of a gun, a ring member mounted for rotation on the projectile during firing thereof, a second group of balls mounted in said ring member and spaced therearound corresponding to the spacing of the first balls, said second group of balls extending outwardly from the surface of the projectile for a distance sufficient for engaging the spiral grooves in the bore of the gun whereby the second group of balls serve as additional ball bearings, the rotative mounting of said ring on the projectile providing compensation for any change in the rate of spiral in the grooves of the gun bore.

5. In a projectile, spaced projectile-rotating means comprising balls seated for rotation in the surface of the projectile and extending outwardly from the surface of the projectile sufficiently for engaging spaced spiral grooves in the bore of a gun, a ring member mounted for rotation on the projectile during the firing thereof, a second group of balls mounted in said ring member and spaced therearound corresponding to the spacing of the first balls, said second group of balls extending outwardly from the surface of the projectile for a distance sufficient for engaging the spiral grooves in the bore of the gun whereby the second group of balls serve as additional ball bearings, the rotative mounting of said ring on the projectile providing compensation for any change in the rate of spiral in the grooves of the gun bore, and a frangible connection between the ring member and the projectile for freeing said ring member to rotate during the firing of the projectile when such compensation is required.

6. In a projectile, a ring member embracing a

- reduced diameter portion of the projectile and rotatable thereon, balls rotatably seated in said ring member at spaced intervals therearound, said balls projecting outwardly from the ring member a distance sufficient for engaging spaced spiral grooves in the bore of a gun, said projectile having additional ball means arranged to engage in such spaced spiral grooves, and having a frangible connection between the ring member and the projectile holding said ring member in fixed position corresponding to a predetermined angle of lead of said grooves, and freeing said ring member to adapt said projectile for operation with a different angle of lead of such grooves.
7. In a projectile having a plurality of recesses in the surface thereof at spaced intervals around the projectile, a ball in each of said recesses, said balls extending outwardly from the surface of the projectile a distance sufficient for engaging spiral grooves in the bore of the gun, and a frangible means connecting each ball with the projectile and adapted to be broken upon insertion of the projectile in the gun bore with the balls in said grooves.
8. A projectile having a plurality of recesses in the surface thereof at spaced intervals around the projectile, balls in said recesses, said balls having from approximately one-half to two-thirds of their diameter extending outwardly from the surface of the projectile for engaging spiral grooves in the bore of a gun, and frangible means securing said balls in said recesses and adapted to be broken upon insertion of the projectile in the gun bore with the balls in said grooves.
